COMBINED LAVATORY, WATER CLOSET AND CABINET

James Alexander Tiller, Louisville, Ky., and Nicholas L. Maczkov, Darien, Conn., assignors to American Radiator & Standard Sanitary Corporation, New York, N.Y., a corporation of Delaware

Filed Aug. 8, 1961, Ser. No. 66,250

Term of patent 14 years

(Cl. D4—2)

FIG. 2

FIGURE 1 is a view, in perspective, of the combined lavatory, water closet and cabinet;

FIGURE 2 is a fragmentary front view showing a portion of the right side of the lavatory cabinet and a portion of the area to the right thereof.

The rear and side not shown are substantially plain. The side of the cabinet not shown is substantially like the side shown except as indicated. The side of the water closet not shown is substantially identical to that shown.

The dominant features of the design reside in the portions shown in full line.

We claim:

The ornamental design for a combined lavatory, water closet and cabinet, substantially as shown and described.
